UNITED STATES PATENT OFFICE

149,151

DESIGN FOR AN ANIMAL WATERING PAN

Pierre D. Southworth, Sturgeon Bay, Wis.

Application May 13, 1946, Serial No. 129,677

Term of patent 3½ years

(Cl. D12—2)

To all whom it may concern:

Be it known that I, Pierre D. Southworth, a citizen of the United States of America, residing at Sturgeon Bay, in the county of Door and State of Wisconsin, have invented a new, original, and ornamental Design for an Animal Watering Pan, of which the following is a specification, reference being had to the accompanying drawing, forming a part thereof.

In the drawing:

Fig. 1 is a perspective view showing the front, top and one side of an animal watering pan, embodying my new design;

Fig. 2 is a front view of the same watering pan;

Fig. 3 is a top view of the watering pan; and
Fig. 4 is a side view thereof.

I claim:
The ornamental design for an animal watering pan, substantially as shown.

PIERRE D. SOUTHWORTH.
